UNITED STATES PATENT OFFICE.

LANSING ONDERDONK, OF NEW YORK, N. Y.

STAMP-AFFIXING MACHINE.

1,289,240.

Specification of Letters Patent. Patented Dec. 31, 1918.

Application filed September 28, 1910, Serial No. 584,195. Renewed May 10, 1918. Serial No. 233,788.

To all whom it may concern:

Be it known that I, LANSING ONDERDONK, a citizen of the United States, residing in the borough of Manhattan, city, county, and 5 State of New York, have invented a new and useful Improvement in Stamp-Affixing Machines, of which the following is a description.

This invention relates to machines 10 adapted for delivering articles of various kinds wound in webs or reels, and has particular reference to mechanism capable of delivering or vending such articles one-by-one successively, and, if required, affixing 15 the same to a given article.

In order that my invention may be more readily comprehended, I have shown the same in connection with a stamp-affixing machine; but, I wish it understood that such 20 illustration is not to be taken as a limitation, but simply as an example of its use.

Among the objects of my invention may be noted the following: to provide a stamp-affixing machine with a feeding mechanism 25 adapted particularly for feeding "perforated articles" such as stamps; to provide a feeding mechanism which will be positive in operation, simple in construction and accurate in its manipulation of the stamp or 30 other article; to provide a feeding mechanism comprising a plurality of yielding points adapted to register with the perforations between the articles and feed the latter by such coöperation; to provide a feeding 35 mechanism which will not tear or mutilate the stamps or other articles, but which will be positive and accurate in its action; to provide means for feeding and counting the articles as they are delivered; to provide a 40 feeding mechanism in combination with a counting mechanism of such character that but one stamp at a time can be fed from the machine and every stamp so fed will be counted, and which cannot be made to de- 45 liver a stamp without a record thereof produced; to provide a moistening device which will be effective, simple and cheap, and which will not waste the liquid; to provide a measuring device which will deliver a 50 small and predetermined amount of liquid to the moistening device, and operate to prevent an excess of liquid being imposed upon the article; to provide an automatic means for filling the moistening chamber, keeping 55 it properly filled, and preventing it from overflowing; to provide means for properly

handling the stamp and presenting it to the moistening means; to provide automatic means for removing the moistening device from coöoperative relation with the article 60 when desired; to provide means whereby the machine may be locked to a table or support and removed therefrom at will; to provide means for preventing the machine from being robbed or the articles taken therefrom 65 under any circumstance without detection or a record thereof being made; and to provide certain novel details of construction involving the feed-drum and its actuating mechanism, the moistening-device, strip- 70 guide and other associated parts which will render the machine positive and accurate in operation, simple in construction and cheap to manufacture.

With the above objects in view, and others 75 which will be detailed during the course of this description, my invention consists in the parts, features, elements and combinations of elements and mechanisms, all as hereinafter described and claimed.

In order that my invention may be fully understood, I have provided drawings 80 wherein:

Fig. 1 is a vertical section of one form of my invention taken substantially centrally of my machine from front to rear and showing the details of construction;

Fig. 2 is a side elevation of the entire machine, a part of the frame being broken away in order to disclose the feeding mechanism;

Fig. 3 is a sectional detail showing the feed-drum-controlling mechanism and other details of construction;

Fig. 4 is a section substantially on the line 95 4—4 of Fig. 3;

Fig. 5 is a side elevation of the drum-controlling mechanism in a position different from that of Fig. 3;

Fig. 6 is a front elevation of the feed-drum, a part being broken out to show details of construction;

Fig. 7 is an elevation of a portion of the base of the machine showing the coöperative arrangement of the counting mechanism 105 and the feeding mechanism;

Fig. 8 is a sectional elevation showing the parts of Fig. 7;

Fig. 9 is a view similar to Fig. 1 showing another form of my invention and the 110 reservoir in two positions.

Fig. 10 is a partial elevation and sec-

tion of the machine of Fig. 9 looking at the opposite side and showing the plunger in the lower position;

Fig. 11 is a perspective view of one form 5 of moistening device and independent stamp or strip-guide;

Fig. 12 is a detail showing the feed-actuating mechanism of the form of Fig. 10;

Fig. 13 is a horizontal sectional view on 10 the line 13—13 of Fig. 9, parts being broken away to show details;

Fig. 14 is a side elevation of the lower portion of the machine of Fig. 10, parts being broken away to show details and the reservoir being shown in two positions;

Fig. 15 is a section on line 15—15 of Fig. 14;

Fig. 16 is a perspective view of the machine locked to a support or base;

Fig. 17 is a perspective view of the support; and

Fig. 18 is a sectional detail showing the means for locking the machine to the support.

Referring to the drawings, in the form of my invention shown in Figs. 1 to 8, the frame-portion of the machine is composed of like parts 1 and 2, secured together by screws or rivets, and also by a cylindrical handle-portion 3, with which coöperates a sliding-sleeve 4, the said parts 3 and 4 producing a chamber 5, within which a spring 6 is housed and which surrounds a plunger 7, the upper end of which is provided with a reduced extension 8, screw-threaded into the head 9 of said sleeve, the said spring engaging a disk 10 at the upper end of the plunger and the circular portion 11 is formed by the two frame-parts 1 and 2 at the bottom. A collar 12 is threaded upon the shouldered lower end 13 of the sleeve 4 and between these two parts packing 14 is applied for the purpose of making an air-tight joint. The head 9 is provided with a plurality of passages 15, extending from the outside thereof into the chamber 5, in which a circular valve 16 is located and supported by the disk 10, providing a slight clearance between the latter and the bottom of the head for the passage of air. The frame is also provided with a cover 17, hinged thereto by pin 18, and forming part of a receptacle, the other portion 19 of which is formed in the two-part frame. The cover is normally closed by means of a latch-portion 20, carried at the lower end thereof and engaging with a catch-portion 21, on the upper end of a reservoir 22, which latter is journaled at 23, so as to swing downwardly from the frame, said reservoir extending clear to the bottom of the machine-frame. The journal of the reservoir is provided with a valve 24, communicating with the tube 25 at its lower end, and the upper end 60 of which communicates with the air-passage

26, extending into the compression-chamber in the handle of the machine. A tube 27 also communicates with the valve at its upper end, the lower end of said tube communicating with the valve 28 in the lower forward end of the reservoir 22, which valve communicates with the reservoir and with the spraying-nozzle 29. The reservoir has in its rear wall a transparent portion 30 and is also provided with a removable bottom-portion 31 and an inlet 32 controlled by a removable screw-plug 33. The receptacle formed in the frame and by the cover has a reel-holder 34, journaled therein at 35, and a reel 36 is supported upon said holder, the web of said reel being threaded through the machine, as shown in Fig. 1. The face-plate 37 is provided in advance of the feeding mechanism and the reservoir, said face-plate having an inclined transverse slot the lower wall 38 of which is beveled to provide a ledger-blade which coöperates with a cutter-blade 40, carried in the cutter-holder 41, secured rigidly to the lower end of the plunger 7. The face-plate 37 is also provided with a passage 42, into which the nozzle 29 projects and through which the stamp is sprayed preparatory to affixing it to the article. A locking-device 44 is carried by the forward end of the reservoir, which coöperates with the frame of the machine in a manner to lock the reservoir in closed position. The head of the plunger is provided with a short, laterally-extending pin 45, traveling in a groove 46 in the frame-portion 1, and at its opposite end is provided with a longer pin 47, extending through a slot 48 in the frame-portion 2, and engaging a lever 49, by means of which the valve or meter 28 is actuated. Some of the parts so far described are substantially the same as in my application, Serial No. 570,234, filed July 5, 1910, and I have illustrated the same to show how the various features of construction are adapted to interact and coöperate for the purposes set forth, and also to accentuate the breadth of my present invention, as well as that of my aforesaid application.

The feeding mechanism of this form of my invention comprises the feed-drum composed of a cylinder or barrel 50, having a plurality of radial apertures or sockets 51, in each of which is set a coiled-spring 52, surrounding a stem 53, and bearing at its outer end against a head 54 of said stem, which head has projecting from it a round-pointed feeding-pin 55, several of which project through each of the plates 56, arranged longitudinally of said drum and set 120 with its surface flush with the surface of said drum. Thus the pins normally project from the periphery of the drum in parallel rows. At one end the drum is provided with a plurality of circumferentially- 130

extending cams 57,—four in number,—or a plate secured to the said drum, the periphery of which is formed into said cams, said cams being produced by tangential surfaces 5 extending from one notch 58 to another around the periphery of said disk or drum. The notches 58 are arranged between the high part of one cam and the low part of the next adjacent cam and just in advance, 10 in the direction of travel of the drum, of a row of feeding-pins 55. The opposite end of the drum is provided with a plurality of studs 59, extending therefrom parallel with the axis thereof, there being four in number 15 corresponding to the four notches and cam surface. The studs are arranged, considering the direction of feed of the drum, just behind the rows of feeding-pins 55. The circumference of the feed-drum, as 20 herein shown, for example, is the exact length or width, as the case may be, of four postage stamps, it being understood that the stamps, or other articles, may be joined by perforations along their lengths or along 25 their widths; and the circumference of the drum may be varied to any extent to accommodate any character of article desired to be vended or delivered or affixed. The cutter-holder 41, which is fixed to the plunger 7, has on its upper surface a lug 60, affording a journal for an actuating-pawl, the long arm 61 of which extends into the path of movement of the pins 59, and the short arm 62 of which is arranged so as to 30 engage a cam 63, provided on the side of the frame-part 1 directly in the path of movement of said arm. Preferably, the arms of the pawl are arranged substantially at a right-angle to each other and the normal 35 position of said pawl is substantially that shown in Fig. 1. The lug 60 is provided with a laterally-extending lug 64, against which the short arm 62 of the pawl engages, said lug operating as a stop to prevent the 40 long arm thereof from being pushed farther down than substantially parallel with the cutter-holder of the plunger. This stop 64, on the one hand, and the cam 63, on the other, constitute means whereby the pawl is 45 positively actuated and is positive in its action in driving the feed-drum and by which the use of springs to return the pawl to operative position is obviated. For every reciprocation of the plunger, the feed-pawl 50 gives a single feed movement to the feed-drum, this feed movement occurring on the upstroke of the plunger. A detent-device comprising the bell-crank lever 65 is journaled in the frame-portion 2 of the machine, just above the feed-drum, as at 66, and having 55 one arm 67 extending substantially horizontally over the periphery of the cams of the feed-drum and the other arm 68 descending substantially vertically into position to coöperate with said cams 57 and the notches 60 of said drum. The arm 67 is provided with an adjustable pin or screw 69, extending therethrough at a right-angle for engagement with the cams and the other arm 68 is provided with a toe 70, for coöperation 70 with said notches. The lever 65 is normally held with its toe 70, in one of the notches 58, as shown in Fig. 3, by means of the spring coiled about the stud or screw 72, projecting from the frame-portion 2 of the 75 machine and maintained under tension by means of a pin 74, projecting from said frame-portion, with which engages the short arm of the spring with a normal tendency to force the long arm 75 of the latter yieldingly into engagement with the bell-crank lever just forward of its fulcrum. Forward of its fulcrum, the bell-crank lever also carries a spring-controlled pawl, one arm 76 of which is held in engagement with 80 an abutment 77, carried by the bell-crank lever by means of the spring 78, fixed to the depending-arm 68 of said lever. The other arm 79 of the pawl is thus held in the path of movement of a pin 80, projecting from the plunger 7, said pin 80, in this instance, being carried by a collar 81, clamped upon said plunger and adjustable thereon by means of the clamping-screw 82. Adjustment of the pin 69 regulates the extent to which the bell-crank lever may be moved so as to force its toe 70 from the notches of the feed-drum. A downward movement of the plunger causes its pin 80 85 to strike the arm 79 of the pawl on its top 90 and thus drive it downwardly against the tension of its spring 78, this movement aiding the spring 75 to keep the toe 70 in co-operative connection with one of the notches 58. The upward movement of the pin 80, 95 striking the arm 79 of the pawl on its under side lifts said arm of the pawl,—the spring 78 having returned said pawl into engagement with the abutment 77 on the lever,—thus operating the lever 68 against 100 the tension of its spring 75 and causing the positive and quick withdrawal of the toe 70 from a notch 58 and causing the pin 69 to engage the periphery of one of the cams 57. See Fig. 5. The swinging 105 of the lever 65, upon its fulcrum, moves the pawl away from the pin 80, thus allowing the latter to pass on its upward movement and the spring 75 to again assume control of lever 65 and return its toe 70 into engagement with the cam-periphery of the feed-drum ready for coöperation with a notch 58. This mechanism operates as a positive lock to prevent overthrow of the feed-drum in either direction, and also has 110 the important function of preventing said drum from being turned more than the length of a stamp or other article by any means other than the plunger. When the toe 70 is out of engagement with a notch 115 120 125 130

58, the screw 69 will be in positive engagement with a cam 57, provided the feed-drum should be advanced sufficiently to pass the notch 58, from which the toe had been 5 lifted, beyond said toe and when the high portion of a cam 57 is engaged with the screw 69, the feed-drum is compelled to stop and cannot be given a further feeding movement until said cam and screw are 10 disengaged. Hence, the feed movement of the feed-drum is positive and intermittent and can only be imparted by the plunger operating the bell-crank lever 65 in the manner described. This is an important feature of 15 my invention because it prevents the removal of stamps or other articles from the machine except as intended and according to the rule of action of the machine.

In order that every feed movement of the 20 feed drum shall be registered and every stamp delivered accounted for, a counting-device 83 of any common construction, such as the Veeder, is secured to the frame-portion 1 on the outside thereof adjacent the 25 feed-drum, said counting-device having connected to its shaft 84 an angular arm 85, extending through a slot 86 in said frame-portion and having its outer end 87 normally held by the spring 88 in the path 30 of movement of the pins 59 in the end of the feed-drum. One of the pins striking the arm-end 87 will move the shaft of the counter sufficiently to cause a registration 35 of the feed-movement and, as the pin passes, the spring will return the arm to its normal position.

From the foregoing description, the mode of operation of this form of my invention will be fully understood from the following:

40 By shifting the latch 44, the reservoir will be unlocked and enabled to swing downwardly away from the feed-drum, this movement releasing the latch 21 from the catch 20 of the cover, enabling the latter to be 45 lifted to open the receptacle for the admission of the reel of stamps or other articles. The reel and holder being inserted in the machine, the end of the web will be passed between the frame-portion 19 and the top 50 of the reservoir, either as shown by full lines, or by dotted lines, in Fig. 1, and thence carried around the feed-drum 50, above the strip-guide 90, and under the stripper-plate 89 and through the slot in the face-plate 37. 55 The cover will then be lowered and the reservoir swung into closed position, by which movement the cover is locked, as will be readily understood. The latch 44 will then be turned to lock the reservoir in working 60 position. This enables the web to snugly encircle that portion of the feed-drum arranged opposite the reservoir and the feed-pins 55 to project through the perforations between the adjacent stamps, or other articles, and into the longitudinal slots of strip-

guide 90, secured to the upper end of the reservoir. If it so happens that the stamp-perforations are not in position to be entered by all of the feed-pins 55, those that do not enter will be depressed into the feed-roll against the tension of their springs. In this connection, it should be noted that it is not necessary that all of the pins in a row shall enter the perforations between articles at the same time; but, it is intended that 70 said pins shall be so spaced that any two or more may register with the perforations, while the others may be depressed by contact with the web or solid portions of the articles, it being understood that perfect 75 and positive feeding is accomplished by the coöperation of one or more of said pins with a like number of perforations. Hence, the importance of this portion of my invention resides in the fact that the feed-pins are so 80 arranged that some of them will always register with the perforations even though the latter should not be equally spaced, or not be in a straight line, thus avoiding the liability of failure to feed the articles, which 85 might result from an attempt to space the pins correspondingly with the perforations; that is to say, it is well known that the perforations between stamps, for example, are not always evenly spaced, nor always in a 90 straight line, so, by making the pins yielding, the stamps are not injured and compensation is had for irregularity in spacing or line-up of perforations. However, the 95 lines or series of feed-pins are spaced approximately the distance between rows of perforations between the articles, and yet, if a greater distance apart, said pins would find the perforations when moved up to them, and cause a proper feed movement by 100 some of the pins entering some of the perforations. Therefore, it will be seen that both circumferentially and laterally, the feed-drum is so constructed that a positive and accurate feed-movement is produced for 105 every successive movement of rotation thereof. The springs 52 are not sufficiently strong to cause the pins to either penetrate or injuriously engage, or bear upon the stamps, should they not happen to register with the 110 perforations. Nevertheless, by reason of the strip-guide 90 and the slots therein, as the feed-drum is rotated, one or more of the pins will find one or more of the 115 perforations between the articles and thus perform the function of positively feeding the same 120 forward for delivery. The plunger will now be depressed, by pressure upon the head 9, which will compress the air within the chamber 5 of the handle, thus causing the 125 valve 16 to close the air-passage in said head. Air will thus be forced through the passage 26, the tube 25, the valve 24, and the tube 27 in the reservoir so as to drive water through the meter or valve 28 and spray the 130

same through the nozzle 29 upon the stamp. During the movement of the plunger downwardly, the pin 47 actuates the lever 49 to actuate the meter 28, thus carrying a measured quantity of water around to the spraying nozzle. Further downward movement of the plunger will cause its pin 80 to push aside the pawl-arm 79 and help to hold the toe 70 in a notch 58, thus holding the feed-drum from movement. Also, the feed-pawl will yield in passing one of the feed-drum-actuating pins 59; and continuation of the downward movement of the plunger causes the cutter to cut a stamp or other article from the web, which will be moistened prior to the cutting operation, and affixed at the end of the down-stroke of the plunger. The feed movement takes place on the return movement or up-stroke of the plunger by the long arm 61 of the feed-pawl engaging one of the pins 59; but, prior to this movement to feed the drum, the pin 80 engages the pawl-arm 79 on the bell-crank lever 65, thus moving the toe 70 of said lever from the notch 58 in the periphery of the feed-drum in which it has been set, after which the pawl arm 61, in its upward movement, will drive the feed-drum to impart thereto the feeding movement. As the plunger continues to rise and its pin 80 passes the pawl-arm 79, the bell-crank lever is forced toward the feed-drum and its toe 70 engages an adjacent cam-surface, said toe being thus ready to drop into a notch as the drum revolves to impart the proper feeding movement. Positive engagement of the toe 70, with a notch 58, is caused by the high portion of the cam 57, engaging said toe so that the latter cannot override the notch into which it should descend, and the spring 75 bearing upon the bell-crank lever 65 forces said toe into said notch, thus stopping the feed movement of the drum at the proper point. This action of the lever 65 causes the pin 69, on arm 67, to be lifted above the path of the high point of the cam 57, as shown in Fig. 3; but, should the drum be turned while the toe 70 of arm 68 is free of a notch 58, the drum would be prevented from having a feed movement,—or being manipulated in any way so as to obtain an article without operation of the plunger 7 or registering its action,—by the engagement of the pin 69 with the high wall of an adjacent notch 58, or by entering said notch, thus locking the drum from movement in either direction. This is an important part of my invention, since the arm 68 and its toe 70 coöperate with the arm 67 and its pin 69 to control the action of the feed-drum and insure its proper action at the proper time. The arm 61 of the feed-pawl, as the plunger 7 moves down, will be lifted by engagement with a feed-pin 59, and subsequently, near the end of the down-

stroke of said plunger, will be depressed or reset, by engagement of arm 62 with cam 63 on the side of the frame-part 2,—see Fig. 1. No overthrow or back-lash of the feeding and controlling devices is thus possible, the feeding movement is positive and the stops between feeding movement are positive, so that only one stamp at a time can be fed from the machine for each complete reciprocation of the plunger, the delivery of the article taking place on the up-stroke of the plunger and only according to the proper action of the machine.

For every feed-movement of the drum, one of the studs 59 engages the lever 85 of the counting-device 83, giving to said lever a complete movement in one direction, thus registering the feed-movement or stamp-delivery, the spring 88 returning said arm to its normal position for coöperation with the succeeding studs on the feed-drum.

Thus it will be seen that for every complete reciprocation of the plunger a complete feed-movement is accomplished, which delivers a stamp from the web in position to be sprayed, cut and affixed, and that said stamp is cut from the web, sprayed, and pressed by the bottom of the cutter-holder upon the article to which it is to be applied. It will also be seen that every feed-movement is counted or registered; that every feed-movement is positive; that, after each feed-movement, the feed-drum is locked against any further feed-movement until the plunger again descends to actuate the feed-drum; and since some of the feed-pins are in coöperation with some of the holes in the strip of articles none of the articles can be drawn through the machine by hand. Hence, every stamp delivered from the machine is accounted for and the filching of stamps from the machine is prevented. And among the important features of my invention is the means by which the registering mechanism and the feeding mechanism co-operate to effect the counting of each and every article delivered, since the feed-drum is guarded against manipulation other than in a regular way; also, the means which prevents operation of the register, except when the drum has been moved far enough to properly feed an article, is important. And by placing the arm 87 and spring 88 out of reach and covering them, they cannot be manipulated from the outside.

In that form of my invention illustrated in Figs. 9 to 15, the general frame-structure, the reel-holder, the cutting mechanism, and the feed-drum are all substantially the same as illustrated in Figs. 1 to 8, inclusive, and these several features and mechanisms have not been shown with the same detail as in Figs. 1 to 8. Figs. 9 to 15 are intended to illustrate an alternative form of feed-drum actuating mechanism, an alternative form

of moistening-device for the stamps or other articles to be delivered, together with certain other features of construction which go to improve the operation and results desired to be attained by my machine. These features will now be described in detail.

As shown in Fig. 9, the cover 17 is provided, on its inside, with a latch-spring 91, secured to said cover by means of a screw 10 92, and having at its outer end a stud 93, which enters an aperture in the frame-portion 19 of said receptacle. The spring is bowed so as to clear a key-hole slot 94, in the cover-portion 17, in which slot may be 15 inserted a key, the tongue of which, when turned, may engage and lift said spring 91, and thereby remove its stud 93 from said aperture, thus releasing the cover-portion 17 and enabling it to be swung outwardly on 20 its pivot 18, for the insertion of the reel.

The moistening-device, in this form of my invention, consists of the receptacle 22, constructed, in general form, the same as that of Fig. 1, but having its forward end 25 95 narrowed, as shown in Fig. 11, in which narrowed end a chamber 96 is formed, which communicates by a valve-chamber 97 with the reservoir in which the liquid is contained. The valve-chamber 97 is provided 30 with a cylinder 98, journaled therein at opposite ends, for free rotation, and in its body is provided with a longitudinal V-shaped slot or groove 99, normally faced toward the reservoir, this slot receiving the 35 liquid from said reservoir and, when rotated, conveying the same to the chamber 96, in the narrowed end of the reservoir-frame. In the chamber 96 is journaled a shaft 100, upon which is fixed a series of absorbent 40 disks 101, of any suitable material, which have a small portion of their periphery projecting through apertures in the upper surface near the forward end of said reduced portion 95 of the reservoir, said disks extending into the chamber 96, which is fed 45 with the liquid by the rotary valve. The shaft of the moistening-device and the shaft of the valve are extended on one side through the frame of the reservoir and each is provided 50 with a pinion, which pinions mesh with each other and are located in the space provided by the reduced forward end of the reservoir. The shaft 100, of the moistening-device, is extended through the end 55 95 of the reservoir and provided with a pinion 102, which meshes with a pinion 103, on the extended journal 104, of the meter or valve 98, see Fig. 11. The extreme end of the moistener-shaft 100, beyond the pinion 102, is provided with another pinion 60 105,—larger than the one 102,—which meshes with a large gear 106, secured to the end of the feed-drum, opposite the end carrying the actuating-pins 59. Hence, rotation 65 of the feed-drum, causing rotation of

the gear 106, will rotate the moistener-shaft pinions 105 and 102, and the latter, in turn, will rotate the gear 103, and rotary valve or meter 98. These movements of the moistener and the valve are intermittently progressive and, for each movement, the moistening-disks present a new wet surface to the article to be moistened, and for every such movement of the moistening-disks the measuring-valve is given a complete rotation, which causes it to carry liquid from the reservoir into the disk-chamber, thus keeping said chamber well supplied with liquid. Hence, the proportion of the pinions 102, 103 and 105 and gear 106 is such 70 as to cause a complete rotation of the meter 98 and of the moistener 101 to a quarter rotation of the feed-drum. This proportion of gear and pinions may be varied, since it is clear that the important feature of this 75 portion of my invention is in automatically measuring and feeding the liquid to the moistening chamber to the extent necessary to keep the latter properly supplied. Moreover, should the liquid in the chamber 96 80 be sufficient to prevent the valve 98 effecting a discharge into said chamber, said valve will necessarily retain the liquid until it can be discharged, since said liquid is under no pressure that will cause it to discharge 85 against the gravity of the liquid in said chamber. Hence, the measuring-valve automatically keeps the liquid in the moistening chamber 96 at a certain height irrespective of the quantity of liquid in the reservoir; and the position of the part, controlled 90 by the valve, is high enough to admit liquid enough to moisten the disks, and no more. This construction and controlling means is 95 also important because it permits carrying 100 any desired quantity of liquid, and enables the moistening means to be brought down close to the base-line of the machine and the stamp close to the article to which it is to be affixed. This correspondingly reduces 105 the amount of plunger action, which is also a desirable feature. However, should the liquid in the disk-chamber 96 substantially 110 fill the same and more be added thereto by the measuring-device, the amount thus added would be, on the completion of the rotation of the measuring-device, removed from the disk-chamber, thus preventing overflow. In other words, the rotary-valve or measuring-device 98 will not only feed liquid into the disk-chamber, but will remove or feed liquid 115 from said chamber when the latter has an excess thereof. This will be readily understood, upon viewing Fig. 9, and is quite an important feature of my invention, since, if the chamber were permitted to fill with liquid quicker than the liquid is used, the liquid would objectionably overflow through the apertures through which the disks 101 120 project. Hence, also the rotary-valve per- 125

forms the double function of feeding liquid to the chamber and preventing the chamber from overflowing, or objectionably filling. As in the other form of my invention, 5 the reservoir is pivoted to the frame at 23, through the medium of a pair of separated lugs 107, between which, upon the journal-pin, is mounted a lever having its forward end formed into a rectangular head 108, 10 and its rear end formed into an elongated, curved arm 109, provided on its bottom with a triangular lug 110. Coöoperating with this lug is the rounded end of a piston-head 111, the rod 112 of which slides through an adjustable screw-plug 113, turned into the lower end of a cylindrical, tubular bearing 114, extending rearwardly from the reservoir-frame, the piston-head sliding in the upper end of said bearing and being normally 20 pressed outwardly or upwardly by means of a coiled-spring 115, encircling the piston-head and bearing at one end against said piston-head, and at the other end against said screw-plug. The curvature of 25 the outer surface of the rearwardly-extending arm 109 is such as to conform accurately with the curvature of the cover 17 and body-portion 19 of the reel-receptacle and said extension is sufficiently long to overlap and 30 coöperate with a portion of the cover 17. In the normal position of the parts, as shown in Fig. 9, the piston-head bears against the lug 110 of the lever-arm 109, thus pressing the latter upwardly against 35 the cover 17, and, since the said cover and receptacle body are unyielding, reverse pressure of the spring tends to swing the reservoir 22 about its journal 23, thus holding its forward end with the moistening-disks in 40 the proper operative relation to the coöperating parts of the machine. This action of the parts normally depresses the rectangular head 108 of the lever, and the strip-guide, the latter, in this instance, consisting of the 45 shank 116, which rests upon the rectangular head and has several screws 117 passing through it into the said head. The body-portion 118 of the strip-guide is curved longitudinally and has longitudinal slots 119 in 50 its curved portion, and at its lower end is enlarged as at 120 and provided at the extreme forward ends with vertically-extending lugs 121, between which a stamp or other article is held and guided during the moistening operation and preparatory to being fed forward and cut off for delivery, or 55 being affixed to a given article. The enlarged forward end 120 of the strip-guide is provided with a series of rectangular apertures 122, spaced correspondingly to the moistening-disks 101, and through which the latter project into engagement with the article to be moistened, as clearly shown in 60 Figs. 13 and 15. On opposite sides of the 65 center aperture 122, in the enlarged end of the strip-guide, longitudinal ribs 123 are located which provide spaced supports upon which the stamp or other article may rest, and at these points, or along the lines of these ribs, the articles will not be moistened, 70 as will be readily understood. Normally, the article will be at rest upon these ribs with the portions over the apertures in engagement with the moistening-disks, and this relation will continue while the machine is in operation; but, when the machine is not in use, or is to be laid aside for any length of time, the reservoir will be depressed, as shown by dotted lines in Figs. 75 9 and 14, so that the moistening-disks will 80 recede from contact with the article, whereupon the ribs will support said article with its moistened parts out of contact with any surrounding portion of the machine, thus preventing said article from sticking to the 85 strip-guide. The reservoir may be depressed and so held against the action of the spring 115 by means of a depressing-lever 124, fulcrumed to the side of the frame-portion 2, near the bottom and rear of the 90 machine. The lever is provided with a finger-piece 125, for manipulating the same, and with a cam-surface 126 which coöperates with a pin 127, projecting laterally from the reservoir through an open-end slot 95 128 in the frame. Hence, when the lever is depressed so that its cam-surface will engage the pin, the reservoir will be swung about its journal 23, thus depressing the forward end of the reservoir and the moistening-device carried therein. To provide for a sufficient depression of the reservoir, the bottom of the latter, at its forward end, is formed with an upward incline 129, which provides sufficient clearance, between the 100 bottom of the machine and the table or support on which the latter may stand, for the forward end to be depressed sufficiently to remove the moistening-disks a proper distance away from the article delivered by 105 the machine. This movement of the reservoir separates the latter from the strip-guide movement of which latter is prevented by the coöperation of the extension 109 with the cover 17. Hence, the strip is not displaced, but is maintained in its proper relation to the feed-pins of the feed-drum, as well as to the strip-guide, stripper-plate and throat-plate, movement of the article laterally of the strip-guide being prevented by 110 the upturned end-lugs 121. Thus, all danger of the article drying after it has been moistened and sticking to the strip-guide is prevented. And the said article is likewise 115 prevented from becoming saturated with moisture, as would be the case were the moistening-disks allowed to remain in contact with the article for any length of time. As before stated, the feed-drum, as regards 120 the feed-pins, the actuating-pins and the 125 130

notched cam-disk, as well as its location in the machine, is substantially the same as in that form of my invention portrayed in Fig. 1.

5 The drum-actuating means, however, have been slightly modified in certain details in that form of my invention shown in Figs. 9 to 15. That is to say, fixed to the top of the cutter-head 41, between the same and the 10 plunger 7, is a plate 130, the forward end of which is provided with a depending bearing 131, lying against, and parallel with, the cutter-head at one side thereof, said plate being also provided with a vertically-extending lug 132, near its forward end. To 15 the bearing is journaled a feed-pawl, the long arm 133 of which extends rearwardly in the path of the laterally-extending pins 59, carried by the feed-drum 50, this arm 20 lying normally substantially horizontal. The short arm 134 of the pawl extends substantially at a right-angle to the long arm and normally substantially parallel with the plunger and is provided with a horizontally-extending lug 135, which coöperates 25 with the lug 132 on the plate. The long arm of the pawl works in a vertical slot 136, in the face-plate 37, the walls of which guide the same and prevent any lateral or 30 springing movement under any circumstance. Journaled in the frame, above the feed-drum, is a controlling-lever 137, given the form substantially of a bell-crank with a portion of one side cut out so as to provide 35 arms 138, the extreme ends of which are in-turned for coöperation with the notches 58, in the periphery of the feed-drum or a plate secured thereto. This lever constitutes part 40 of a drum-controlling or detent mechanism and has an extension 139 back of its pivotal point 140, with which coöperates a spring 141, the normal tendency of which is to force the lower in-turned end or toe 142 into engagement with one of the notches 58, or 45 into engagement with one of the peripheral cams 57. Just in rear of its pivot, the controlling-lever has fulcrumed to it an actuating-dog or tappet in the form of a bell-crank lever, one arm 143 of which extends 50 toward the plunger and the other arm 144 of which extends downwardly and coöperates with a lug 145, extending laterally from the lever 137. A spring 146, surrounding 55 the journal of the dog and having one end bearing upon the top of the controlling-lever and the other end bearing upon the dog, keeps the latter normally in engagement with the lug, this being the operative position of the dog to lift the controlling-lever from engagement with the feed-drum 60 so that the latter may be given a feed movement. A cam-projection or collar 147 is fixed to the plunger 7, in proper coöoperative relation to the dog, and is provided on its actuating-face with an inclined surface or 65 cam 148. As the plunger moves downwardly, the cam engages the arm of the dog, presses it downwardly against the power of its spring, thus tending to force the in-turned end or toe 142 of the controlling-lever into 70 a notch 58 of the feed-drum, thus preventing the same from having any movement during the downward movement of the plunger. This is essential, since on the downward movement of the plunger the 75 actuating-pawl engages a pin 59, with a tendency to rotate the feed-drum, such rotation being prevented by the controlling-lever, the toe of which, as just stated, co-operates with one of said notches and is held 80 firmly therein by the combined action of the spring and dog. As the plunger reaches substantially its lower limit of movement, the arm 133 of the feed-pawl passes the pin with which it engages on its downward 85 stroke and substantially at the same time the cam 63 tilts it back into its substantially horizontal position, shown by the dotted lines in Fig. 12. Substantially at the same time, the controlling-dog is released by the 90 cam-collar 147 and allowed to assume the position shown in Fig. 10, with its depending-arm in engagement with the lug 145 of the controlling-lever. In this condition, the 95 feed-drum is locked against a feed movement, the feed-pawl is ready to impart a feed movement to the feed-drum and the controlling dog is ready to lift the toe of the controlling-lever from engagement with the notch 58. The upward movement of the 100 plunger causes the cam-collar to engage the horizontal arm of the dog, which, through its depending-arm, operates the controlling-lever and moves its detent-toe 142 from the notch 58, thus freeing the feed-drum preparatory to a feeding operation. Subsequently, on the continued upward movement of the plunger, the long arm of the feed-pawl engages the pin immediately above it and as said pawl is now rigidly set with its 110 short arm against the lug 132, the feed-drum is given a movement of rotation corresponding in extent with the movement of the feed-pawl until the latter has passed by the co-operating-pin, the latter, during the rotation of the drum, moving in the arc of a circle away from and off the end of said feed-pawl. The parts are so proportioned and the extent of their movements is such 115 that an article of a given length, such as a stamp, for example, is fed forward along the strip-guide, by the feed-pins of the feed-drum, under the stripper-plate and through the throat-plate into position to be severed by the cutter 40, on the succeeding downward movement of the plunger. The sequence of operation of this form of my invention is substantially the same as that of the form shown in Figs. 1 to 8, since the feed 120 movement of the drum takes place on the 125 actuating-face with an inclined surface or 130

upstroke of the plunger and the severing action occurs on the downstroke of the plunger, during which downstroke an article is moistened. There is this difference, however, between the operations of the machine of the two forms of my invention, viz., that on the downstroke of the plunger, in the form of my invention shown in Figs. 1 to 8, that article which is to be immediately severed is sprayed just previous to being severed; but, in the form of my invention shown in Figs. 9 to 15, that article which is severed on the downstroke of the plunger has been moistened by the moistening-device 10 on a previous downstroke of the plunger, in consequence of which the article, when fed forward on the upstroke of the plunger, is moistened and ready for the severing and affixing operations. In other words, in the 15 form of Fig. 1, the moistening takes place after the feed-stroke and substantially simultaneously with the severing operation, while in the form of Fig. 9 the moistening occurs during the feeding action and before 20 the severing movement of the plunger begins. In the form of my invention shown in Figs. 9 to 15, the roll of articles is inserted in the machine by unlocking the cover 17 and swinging it up, thus enabling the 25 strip-guide and reservoir to be swung downwardly out of the way and out of coöperation with the feed-roll. The reel is then inserted and the end threaded down to the feed-drum, as in Fig. 1, the pins on the feed-drum being entered into the perforations of 30 the stamps. The strip-guide and the reservoir are then swung back and the cover 17 closed, whereupon the spring-catch 91 locks the parts in place. By this it will be seen 35 that the stamp-receptacle and strip-guide are locked one by the other and independently of all other parts of the machine.

From the foregoing description, it will be seen that the moistening mechanisms are interchangeable, as are also the feed-drum-actuating mechanisms, it requiring, in either instance, but a slight change in one or the other of the frames and parts of the machine of Figs. 1 to 9 to adapt any of the 40 mechanisms thereto. In other words, with only a few slight changes in the frame-parts of Figs. 1 and 9, the moistening-device in either of these figures can be interchanged, likewise the feed-drum-actuating 45 means.

I desire to stress again that important feature of the feed-actuating mechanism which involves the idea of means of preventing any feed movement of the feed-drum taking place until after the plunger 50 has been moved to its lowermost limit, and then caused or allowed to ascend to approximately the point indicated by the parallel lines α , in Fig. 12, at which time the feed-drum is released by the controlling-lever

preparatory to a feed action, the said feed-drum being up to such times positively locked against a feed movement. In consequence, a person may fool or tamper with the machine indefinitely by reciprocating 55 the plunger between extremes, but until the extreme of downward movement has been reached no feed movement can be imparted to deliver articles from the machine. Hence, the machine is safe against any attempt to extract a stamp or article without being accounted for and every article that is delivered is registered on the counting-device, which, obviously, can be applied to the form of my invention shown in Figs. 9 60 to 15 in the same manner as shown in the form of my invention of Figs. 1 to 8.

In the foregoing description, I have described my machine more particularly with reference to its portable character, since it 65 is obvious that, by reason of its compact structure and simple form, it can be easily handled and carried about the office, or from place to place, without restriction and readily used for affixing stamps or labels to 70 bulky packages; but, there are times when, and conditions under which, it may be desirable or necessary to fix the machine in position upon a table or desk so that it may not be carried away and that it may always be 75 readily found or located for use. With this object in view, I have provided a support or fixture to which my machine may be detachably secured and firmly locked in place 80 against removal and at the same time prevent tampering with the machine, or removing the stamps or articles in any manner. This part of my invention is illustrated in 85 Figs. 16 to 18, wherein the support is shown to consist of the front platform or receiver 90 150, a rear portion or support 151, in the center of which is a dove-tail groove 152, in which the machine is set. The support may be secured to a table, desk, or other piece of 95 furniture, by means of screws 153 passing through the bottom of the groove and into 100 said furniture. The bottom of the groove is elevated from the surface of the platform a short distance, as indicated at 154, this being 105 for the purpose of separating the forward or delivery end of the machine from the said platform and so as to enable thin, flat articles, such as letters, to be slid under the delivery end of the machine for the purpose 110 of having a stamp affixed thereto in the event the machine is used for that purpose. For the purpose of coöoperating with the 115 overhanging portions 155 of the groove, the machine is provided along its bottom, on opposite sides, with longitudinal ribs or 120 flanges 156, of a size sufficient to fit snugly but slide freely in the said groove. Hence, the machine can have in said groove only 125 longitudinal movements parallel with the surface of the support. In order to securely

lock the machine in the support, a spring-controlled latch, in the form of a lever 157, is pivoted at 158 within one of the portions 151 of the support, the same being made hollow for the purpose. As shown in the drawings, the right-hand portion is so constructed, and the lever 157 is pivoted therein and is provided at its forward end with the locking-tongue 159, given any form desired 10 and coöperating with a recess 160, in the adjacent flange 156 of the machine-frame. To limit the forward or locking position of the lever, the latter is provided with the extension 161, coöperating with the stop 162, 15 fixed at 163, by means of a screw. The locking-lever is normally held in locking position by means of a spring 164, normally engaging the lever and pressing it toward the recess 160 and the flange 156, the spring 20 being fixed in place by means of the screw 165. In order to release the machine from its support, the locking-lever may be manipulated by means of a key entered through the hole 166 in the support, so that its 25 tongue may engage the lever and thus move it against its spring control and thus remove the locking-tongue 159, from the recess 160, in the flange 156. Hence, the machine is firmly locked in its support and yet capable 30 of being quickly removed by one in possession of the key.

Having thus described my invention, what I claim and desire to secure by Letters Patent is:

35 1. A machine having, in combination, means for delivering articles therefrom including a reciprocatory plunger; means for moistening the articles; means for affixing the articles as delivered; a rotary feed- 40 drum; a lever mechanism between said drum and said plunger; said lever mechanism including means movable with respect to the plunger and means coöperating with the drum for preventing movement being im- 45 parted to the drum except as the result of a predetermined movement of said plunger.

2. A stamp-affixing machine having, in combination, a receptacle for the stamps, means for delivering stamps from the machine, a moistening device, and coöperating 50 means for locking the receptacle and moistening device for operation in the machine, said means being arranged so as to prevent the moistening device being released till the receptacle is opened.

3. A stamp-affixing machine having, in combination, means for delivering stamps, a movable moistening-device coöperating with the delivery means, and means for yieldingly 55 holding the moistening-device in coöperative relation to the delivery means.

4. A stamp-affixing machine having, in combination, means for delivering stamps, a strip-guide coöperating with the delivery

means, a pivotally supported moistening device coöperating with the delivery means and guide, and means for moving the moistening device out of coöperative relation to the guide and delivering device.

5. A stamp-affixing machine having, in combination, means for delivering stamps; means for moistening stamps located under the delivery means; a strip-guide for directing the stamps over the moistening means; means for mounting the guide on the moistening means so as to be movable relatively thereto; and means carried by the strip-guide for preventing lateral movement of the stamps thereon.

6. A stamp-affixing machine having, in combination, means for delivering stamps, means for moistening stamps, a strip-guide for the stamps, said guide being provided with supports above the moistening means to hold the stamps from engagement with the moistening means at certain points.

7. A stamp-affixing machine having, in combination, means for delivering stamps, a moistening device movable on the machine, a strip-guide movable relatively to the machine and moistening-device, and means whereby the moistening-device may be moved from coöperative relation with the delivering device and guide and for holding the guide in coöperative relation with the delivery means.

8. A stamp-affixing machine having, in combination, a stamp delivering means and stamp moistening means, the latter comprising a rotary moistening and liquid measuring device, and means for actuating the several elements with a ratio of a complete rotation of the measuring device and moistening means to a quarter turn of the delivery means.

9. A stamp-affixing machine having, in combination, a stamp delivering means and stamp moistening means, the latter comprising a rotary moistening and liquid measuring device, and means for actuating the several elements with a ratio of a complete rotation of the measuring device and moistening means to a fractional turn of the delivery means.

10. A stamp-affixing machine having, in combination, means for delivering stamps, means for moistening stamps, means whereby the moistening means may be moved from operative position, and means for holding the stamps out of contact with the delivery means and the moistening means when the latter is moved to an inoperative position.

11. A stamp-affixing machine having, in combination, means for delivering stamps, means for moistening stamps, a cutting mechanism, and means for supporting the stamps at predetermined points out of en-

- gagement with the moistening means until after said stamps have been delivered beyond the cutting mechanism.
12. A stamp-affixing machine having, in combination, means for delivering stamps, means for moistening stamps, cutting mechanism for coöperating with the stamps, and means for supporting the stamps between the moistening means and the cutting mechanism to prevent the moistened parts of the stamps contacting with any part of the machine before being applied to an article.
13. A stamp-affixing machine having, in combination, means for delivering a stamp therefrom, and means for moistening a stamp before delivery, said last named means being adjustably mounted on the machine so as to be movable relatively to the machine into and out of operative position with respect to the stamp.
14. A stamp-affixing machine having, in combination, means for delivering a stamp therefrom, and a reservoir and means carried thereby to engage the stamp and moisten the same before delivery, said reservoir and moistening means being adjustably mounted to be movable into and out of operative position.
15. A stamp-affixing machine having, in combination, delivery means for the stamps, a moistening device for the stamps, and a support for the stamps arranged adjacent the delivery means and the moistening device to normally hold the stamp away from the moistening device at separated points.
16. A stamp-affixing machine having, in combination, stamp delivery means, stamp moistening means, and a support arranged between the delivery means and the moistening means, said support being provided with apertures through which the moistening means projects to engage the stamps.
17. A stamp-affixing machine having, in combination, stamp delivering means, means for moistening the stamp, a measuring device for supplying liquid to the moistening means, and connections for causing the measuring device to be actuated in accordance with the operation of the stamp delivering means.
18. A stamp-affixing machine having, in combination, stamp delivering means, means for moistening the stamp, a rotatable measuring device for supplying liquid to the moistening means, and means for actuating the measuring device in accordance with the operation of the stamp delivering means.
19. A stamp-affixing machine having, in combination, means for delivering stamps, means for moistening stamps, means whereby the moistening means may be moved from operative position, and means for holding the stamps out of contact with the delivery means and the moistening means when the latter is moved to an inoperative position.
20. A stamp-affixing machine having, in combination, stamp delivering means; means for applying moisture to the stamp by contact therewith; a measuring device for supplying liquid to the moisture-applying means; and connections for causing the measuring device to be actuated in accordance with the operation of the stamp delivering means.
21. A stamp affixing machine having, in combination, stamp delivering means; means for applying moisture to the stamp by contact therewith; a rotatable measuring device for supplying liquid to the moisture-applying means; and means for actuating the measuring device in accordance with the operation of the stamp delivering means.
22. A stamp-affixing machine having, in combination, stamp delivering means, means for moistening the stamp, a rotatable measuring device for supplying liquid to the moistening means, and means for actuating the measuring device in accordance with the operation of the stamp delivering means.
